Primary Examiner — Cynthia Ramirez

Assistant Examiner — Michael A Maharajh

(57) **CLAIM**

The ornamental design for a facial massage device, as shown and described.

DESCRIPTION

FIG. 1 is a perspective view of a facial massage device showing my new design;

FIG. 2 is a another perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is bottom plan view thereof; and,

FIG. 9 is another perspective view shown in a condition of use.

The broken lines shown in the drawings are for the purpose of illustrating portions of the facial massage device, which form no part of the claimed design.

1 Claim, 9 Drawing Sheets
